FUEL INJECTION SYSTEM FOR COMPRES-
SION-IGNITION ENGINES

Sydney Hinchcliffe, Wylam-on-Tyne, England

Application February 13, 1941, Serial No. 378,832
In Great Britain January 29, 1940

4 Claims. (Cl. 123—139)

This invention relates to fuel injection systems for compression ignition engines.

In the conventional fuel injection systems the fuel oil in the system—from the injection pump to the injection valve—is stationary up to the point of opening of the injection valve. The result is that when the injection valve does open there is a substantial drop in the pressure of the oil at the injection nozzle, so that provision has to be made for compensating for this. Otherwise the reduced pressure will result in poor atomisation and therefore delayed ignition, with the further result that additional oil is being forced into the combustion chamber without being ignited, so that when ignition does occur there is an excessively rapid rise of cylinder pressure which produces excessive maximum pressures and temperatures in the engine. This compensation has been effected by increasing the pressure generated by the pump to impart the necessary high acceleration to the stationary oil in order to build up and maintain the pressure at the injection nozzle at that necessary for atomisation. However, as is well known, such pump pressures are of excessive magnitude and require pumps of such superlative precision that their production can be undertaken only by manufacturers possessing special facilities.

It is the object of the present invention to provide means whereby such excessive pump pressures may be obviated, while at the same time the necessary injection pressure may be maintained under precise control and so the point of ignition more accurately determined, with the further result that engines may be run more smoothly with reduced maximum pressures and temperatures with the still further result of increased power/weight ratio. Another object is simultaneously to provide means whereby a substantially finer degree of atomisation is attained than hitherto, so that engines may be run effectively on a wider range of fuel oils than has been hitherto possible with conventional fuel injection systems. A further object is to provide means which will nullify the effect of the expansion and contraction of the fuel oil pipe owing to the high pressures which have to be generated by the pump.

A number of proposals have been made which included the use of an accumulator piston which was adapted to move under the increasing oil pressure on the pressure stroke of the fuel pump until a predetermined oil pressure was attained, whereupon the injection valve opened and injection took place, the accumulator piston being free

to continue its movement so that the injection pressure—thus depending solely on the static pressure in the oil system—remained substantially constant. Such proposals included the use of an injection valve connected to the accumulator piston through a lost motion arrangement, so that after a predetermined movement of the said piston the injection valve was opened and continued to open in accordance with the difference between the increasing oil pressure and the pressure drop due to the opening of the injection valve.

The fuel injection system according to the invention comprises an injection valve adapted to be maintained on its seating by the fuel oil pressure, a fuel pipe, a pressure accumulator comprising a cylinder and a piston in said cylinder, said piston being adapted to be subjected to the pressure of the oil in the system, the area of said piston being greater than that of the injection valve subjected to the fuel oil pressure, means for arresting the movement of said piston at about the time when commencement of injection is due, and lost motion means operatively interposed between said accumulator piston and said injection valve for opening said injection valve after the said piston has moved for a predetermined distance under the rising oil pressure, the arrangement being such that subsequent movement of the said piston before its arrest is only sufficient to lift the fuel injection valve the requisite amount for efficient fuel injection.

The invention will now be described by way of example with reference to the accompanying drawing.

In the said drawing:

Fig. 1 is a diagrammatic longitudinal sectional view of a form of the invention comprising a combined pressure accumulator and cylinder.

Fig. 2 is a diagrammatic longitudinal section of an alternative form of pump to be used instead of the pump shown in Fig. 1.

Referring more particularly to Fig. 1, 1 is an accumulator cylinder, and 2 the accumulator piston. 3 is an enlarged cylinder communicating and in axial alignment with the cylinder 1. The cylinder 3 houses a compression spring 4 whose lower end abuts against the piston 2. The upper end of the cylinder 3 has a vent 3a to prevent the building up of pressure.

The piston 2 is adapted to abut against an adjustable abutment screw 5 to limit its upward travel. The lower end of the piston 2 projects into an enlarged cavity 6, and is T-slotted at 2a to receive the headed end 7a of the valve stem 7

of a fuel injection valve $7b$. The lower face of the head $7a$ is adapted to abut against the shoulder $2b$ formed by the T-slot. The difference between the length of the head $7a$ on the one hand and the distance between the inner face of the slot $2a$ and the inner face of the shoulder $2b$ on the other hand is slightly less than the distance between the end of the abutment screw 5 and the upper end of the piston 2 , by an amount equal to the lift necessary for the valve $7b$.

The spring 8 is purely supplementary, and ensures the valve $7b$ being retained on its seating when the engine is stopped and there is no oil pressure.

Oil is forced by the pump B through the pipe 10 into the cavity 6 below the piston 2 , and the resulting oil pressure causes the piston 2 to move upwards; but it maintains the valve $7b$ on its seating until, after moving upwards for a certain distance, the shoulder $2b$ of the piston 2 abuts against the under side of the head $7a$, and so begins to lift the valve $7b$, lifting continuing until the movement of the piston 2 is arrested by the abutment screw 5 .

Owing to the movement of the piston 2 , the oil is able to gain momentum through the pipe 10 , but immediately after the opening of the valve $7b$ the piston 2 is arrested by the stop 5 , thus arresting the movement of the oil which as a result generates a pressure in the cavity 6 and so at the valve $7b$.

After injection, the pump pressure is relieved, and the accumulator piston 2 returns to its original position, displacing the oil in the accumulator cylinder 1 , through the passage 10 , suitable means being provided in the fuel pump B for receiving the oil. The said oil receiving means may comprise, as shown, a spill valve 11 , the oil passing from the passage 10 to the discharge port B' of the pump B where the spill valve 11 will have been lifted, thus allowing the oil to escape to the suction chamber B^2 of the pump B .

An injector as shown in Fig. 1 may be used, if desired, with fuel pumps such as that shown in Fig. 2, that is to say pumps which spill from the pump cylinders, and not from the delivery passage as is the case with the pump B of Fig. 1. The delivery valve 12 of the pump C shown in Fig. 2 may have a portion of it arranged to act as a piston $12a$ as shown. With such an arrangement the fuel pump now delivers oil to the accumulator cylinder until the accumulator piston has reached its stop 5 . Injection then commences and continues until the spill valve 13 opens. At this point the delivery valve 12 closes, but owing to its piston portion $12a$ there is displaced along the pump delivery pipe by the piston 2 a volume of oil equal to the volume of the said piston portion, thus allowing the valve $7b$ to seat and the piston 2 to maintain a pressure on the oil.

The motion of the accumulator piston 2 is finally arrested by the valve head $7a$ or by the oil trapped in the system when the delivery valve reaches its seat, according to the relative volumes displaced by the accumulator piston 2 and the piston portion $12a$ of the delivery valve 12 . By keeping the volume of the piston portion $12a$ less than the maximum displacement of the accumulator piston, the delivery valve 12 seats before the accumulator piston reaches the valve head $7a$, and the pressure is thus maintained on the oil system between consecutive periods of injection. When the succeeding delivery of the pump begins, a volume of oil approximately equal

to that of the piston portion $12a$ is moved along the pipe 10 before the piston 2 begins to lift the valve $7b$. Thus the oil in the pipe 10 is accelerated before injection starts, and so has been allowed to gain momentum.

It will be observed that the oil pressure except when injection is taking place is forcing the injection valve $7b$ on to its seat, thus tending to prevent leakage.

10 In the conventional arrangement there is a delay between the commencement of pump delivery and the opening of the injection valve due to the expansion of the pipes and other parts from a small pressure to the high pressure necessary to open the injection valve. This causes variations in the actual point of injection and reduces the engine efficiency.

With the smaller pressure increases required by the arrangement according to the invention 20 this drawback is obviated and a more delicate control of the fuel ignition point may be effected.

Again, owing to the fact that the suitability of Diesel engine oils depends on the rapidity with which they ignite, and as ignition is a function 25 of initial atomisation, the invention permits the use of a wider range of fuels than hitherto.

The advantages above set forth are more marked in contrast with the conventional fuel 30 injection systems at high engine speeds. The operation of the system according to the invention is practically independent of the engine speed, and therefore is of special advantage for variable speed engines.

Another result of the system according to the 35 invention effects the fuel nozzle. The size of nozzle orifice is chiefly a function of the fuel quantity, the duration of the injection and the mean pressure of the fuel. As the system according to the invention reduces the mean fuel pressure, the size of orifice can be increased. The nozzle is therefore cheaper to make but also makes possible the use of orifice shapes other than circular or annular—which are not necessarily the best—for atomising. This effect is progressive because by using a more efficient atomising shape the pressure can again be reduced and so on.

What I claim as my invention and desire to 50 secure by Letters Patent of the United States is:

1. A fuel injection system comprising an injection valve adapted to be maintained on its seating by the fuel oil pressure, a fuel pipe, a pressure accumulator comprising a cylinder and a piston in said cylinder, said piston being adapted to be subjected to the pressure of the oil in the system, the area of said piston being greater than that of the injection valve subjected to the 55 fuel oil pressure, means for arresting the movement of said piston at about the time when commencement of injection is due, and lost motion means operatively interposed between said accumulator piston and said injection valve for opening said injection valve after said piston has moved for a predetermined distance under the oil pressure, the arrangement being such that subsequent movement of the said piston before its arrest is only sufficient to lift the fuel injection valve the requisite amount for efficient fuel injection.

2. A fuel injection system according to claim 1, a shoulder on the accumulator piston, said shoulder being adapted to engage an abutment on the

injection valve after the predetermined amount of movement of said piston has taken place.

3. A fuel injection system according to claim 1, wherein the accumulator piston has formed thereon a T-slot, an abutment screw adapted to abut against the inner end of the accumulator piston, a valve stem integral with the injection valve, a head on the end of said valve stem, said head engaging with the T-slot in the accumulator piston, a spring adapted to press the inner wall of said T-slot against the outer face of said head, while the lower face of said head is adapted to abut against the shoulder formed by said T-slot, the difference between the lengths of said head and the distance between the inner face of said slot and the inner face of said shoulder, being

slightly less than the distance between said abutment screw and the piston when the injection valve is closed, by an amount equal to the lift necessary for the injection valve.

4. A fuel injection system according to claim 1, comprising means for maintaining the pressure during the period between consecutive injections in the fuel oil pipe line at a value approximating that required for injection, said means comprising a fuel pump delivery valve having a piston portion thereon which allows its own volume of oil to move along the fuel pipe before opening and closing of the said delivery valve, and a spill valve between said delivery valve and the fuel pump.
